UNITED STATES PATENT OFFICE.

GEORGE W. TERRY, OF NASHVILLE, TENNESSEE.

DUST CAP.

Application filed November 11, 1922. Serial No. 600,312.

To all whom it may concern:

Be it known that GEORGE W. TERRY, a citizen of the United States, residing at Nashville, in the county of Davidson and State of Tennessee, has invented certain new and useful Improvements in Dust Caps, of which the following is a specification.

This invention relates to the provision of an arrangement whereby the dust cap at present used to protect the valve stem of an inner tube may be more quickly and readily removed and replaced.

More specifically this invention contemplates the use of a spring member within the recess of the enlarged end of a dust cap, said spring having a portion adapted to project without the recess for engagement with suitable grooves in a lock washer, whereby such dust cap and the washer are prevented from having any relative motion.

The present invention also includes convenient means for permitting the manipulation of the spring member whereby same can be withdrawn from its locked position in the groove to permit the removal of the cap.

With these and other objects in view reference will be had to the accompanying drawings forming a part of this specification and wherein like numerals of reference designate corresponding parts throughout the several views, in which:—

Fig. 1 is a side elevation showing a wheel section with the improvement attached.

Fig. 2 is a partial vertical sectional view showing that portion of the dust cap and valve stem including the present invention.

Fig. 3 is a bottom plan view of the dust cap showing the spring in position, and

Fig. 4 is a plan view of the washer.

Referring now to the specific construction involved in the present invention, the conventional valve stem A is shown fixed to the inner tube a' and extending through the wheel felly B shown in section. The valve stem is provided with screw threads throughout its entire length and these threads are interrupted by the flat faces a as is well known in the art. The dust cap D is provided with threads corresponding to the threads on the valve stem and indicated by reference character d. These threads are not continuous but are broken throughout opposite longitudinal faces which correspond to the flat faces a of the valve stem. From this arrangement, it will be seen that the cap can be placed in position without engagement

with the threads by having the flat faces a of the stem register with the smooth surfaces d' forming the interrupted thread portions.

The open end of the cap D has seated within the hexagonal recess E the spring e, the latter following the inner contour of the wall forming the recess and having the radiating arm f projecting through the opening g formed therein. The end of the arm f projects upwardly at right angles to its body portion for a short distance and at a point spaced from the outer wall of the cap, and then is again bent to extend in a line parallel with its body to form the handle 70 or gripping arm h.

The spring e is soldered or otherwise suitably fixed to the inner wall of the recess at a point diametrically opposite the opening g, the point of engagement in the present instance indicated by the letter i being spaced downwardly from the upper wall of the recess so as to locate the lower face of the spring flush with the lower face of the cap. The arrangement permits the proper seating of the cap on the washer plate F.

The washer plate F is provided with a central opening having the flat sides adapted for engagement with the flat faces a of the valve stem so that when in position rotary movement is prevented. The upper face of the washer is formed with the grooves k, k' which radiate from the central opening and have a common axis which extends through the center of the washer plate. It will be noted that these grooves extend from the curved walls of the opening and by this arrangement it will be obvious that when the washer plate is in position on the valve stem they register with the threaded portions of the valve stem at all times. Any suitable packing may be provided as indicated at G, between the plate F and felly B for preventing water and dirt from passing through the felly and injuring the tube.

Referring again to the spring member e attention is directed to the fact that normally the free end projects below the lower face of the cap so that when the cap is in position and properly rotated to cause the registration of the radiating arm with one of the grooves k, k', the arm will seat in such groove and the cap will be prevented from rotating. By referring to Fig. 2, it will be evident that to procure the arrangement of the spring as above indicated it is necessary to fix the spring at an angle to the trans-

verse axis of the cap. When it is desired to release the cap to permit the removal of same the gripping arm *h* is engaged and elevated to withdraw the arm *f* within the slot *g*. The cap can then be rotated to permit the disengagement of the threaded portion.

Attention is directed to the fact that although the washer is not threaded or otherwise locked in position on the stem, nevertheless due to pitch of the threads, when the cap is forced into position and the threads of the stem are engaged by the threads of the cap, the downward movement of the cap caused thereby will result in binding the washer firmly against the felly. This will eliminate any possibility of the cap rattling or causing any noise. The packing *G* will also assist in the firm seating of the washer by permitting a slight elastic action as the latter is secured in locked position.

Numerous changes in detail of construction and arrangement of parts may be made without departing from the spirit of the invention.

25 What I claim as new and useful and desire to secure by Letters Patent, is:—

1. In combination with a felly, a valve stem, a washer supported on said felly and having grooves formed in one face, a dust

30 cap, and a spring permanently attached to said dust cap adapted to seat in one of said grooves.

2. In combination with a felly, a valve stem, a grooved washer on said valve stem and engaging said felly, a dust cap formed with a recess, a spring located within said recess and normally projecting without said cap and engaging said grooved washer, and a gripping arm for said spring.

40 3. In combination with a valve stem, a washer carried thereby provided with a groove in its upper face, a dust cap, a recess in said dust cap, the wall of said recess being notched, a spring fixed within said recess and projecting through said notch, said spring normally seating in said groove, and an arm projecting upwardly from said spring and being spaced from the outside wall of said cap.

50 4. In combination with a valve stem, a grooved washer carried thereby and fixed against rotation, a dust cap, a hexagonal spring located within said dust cap, one end of said spring being fixed to the inner wall

of said cap flush with the bottom face of 55 said cap, and the opposite end of said spring projecting downwardly for engagement with said grooved washer, and terminating in a handle portion spaced from the outer wall of said cap.

5. In combination with a valve stem, a washer carried thereby and fixed against rotation, grooves radiating from the central axis of said washer in the upper face thereof, a dust cap, a fixed spring within the said cap arranged at an angle to its horizontal axis, the body of said spring following the inner wall of said cap and terminating in an off-set handle portion, a portion of said spring being adapted to engage and seat 70 within one of said grooves.

6. In combination with a valve stem, a washer carried thereby and fixed against rotation, grooves formed in the upper face 75 of said washer and radiating from its central axis, a dust cap formed with a recess in its lower end, the wall of said recess being notched, a fixed spring within said recess, the body of said spring following the inner wall of said recess at an angle to its horizontal axis and projecting through said notch without said cap, the portion of said spring without said cap being spaced from the outer wall of said cap and projecting upwardly and outwardly to form a handle, and the portion of said spring projecting through said notch being adapted for engagement with the grooves in said washer.

7. A valve stem, a washer plate formed with a recessed upper face, a dust cap 90 formed with a recess, a spring member rigidly attached to said dust cap within said recess and projecting downwardly at an angle to the transverse axis to engage the upper face of said washer.

8. In combination with a felly, a valve stem, a washer carried by said valve stem and fixed against rotation, the upper face of said washer being formed with grooves, a dust cap formed with a notch in its lower edge adapted for registration with the grooves in said washer, and a member adapted to normally engage said registering groove fixed to said cap and being capable of upward movement into said registering 105 notch.

In testimony whereof I affix my signature.

GEORGE W. TERRY.
